UNITED STATES PATENT OFFICE.

JOSEPH F. SADLER, OF LOS ANGELES, CALIFORNIA.

SAMPLE-HOLDER.

No. 877,599.

Specification of Letters Patent.

Patented Jan. 28, 1908.

Application filed November 19, 1906. Serial No. 344,052.

To all whom it may concern:

Be it known that I, JOSEPH F. SADLER, a citizen of the United States, residing at Los Angeles, in the county of Los Angeles and

5 State of California, have invented new and useful Improvements in Sample-Holders, of which the following is a specification.

My invention relates to means for holding samples of cloth that is carried in stock in 10 bolts; and the object thereof is to provide means to hold a sample of the cloth of which the bolt is composed in a position of convenient access and to be able to furnish prospective purchasers of cloth from the bolt 15 with a sample of the same at a minimum of expense.

Heretofore it has been the custom among dry goods merchants to furnish prospective customers with samples from bolts of cloth 20 by cutting off from the free end of the cloth a short piece thereof and of sufficient size to enable the customer to tell the character and quality of the cloth when away from the store. These samples are usually cut from 25 one side of the bolt, thereby leaving the end of the cloth with a notch cut out of the corner, and when a piece of cloth is purchased from the bolt, measurement is taken on the side of the notch, and so much of the cloth as 30 was not cut out when the notch was taken therefrom goes to the purchaser without the merchant being paid therefor, and it is one of the objects of my invention to do away with 35 the necessity of cutting these pieces from time to time from the bolt of cloth.

In the drawings: Figure 1 is a perspective view of my improved sample holder detached from the bolt. Fig. 2 is a perspective view of a bolt of cloth provided with my 40 proved sample holder. Fig. 3 is a longitudinal section of my improved sample holder with a sample in place therein and with the bolt of cloth shown in dotted lines.

I prefer to form the body of my sample 45 holder of sheet metal 6 with the edges thereof turned over a wire frame 7. The front end of this wire frame is preferably bent downwardly, and the front end of the body is likewise bent downwardly as shown in Fig. 3, 50 the position of the sample holder shown in Fig. 1 being upside down. The edges of the down turned portion of the body are turned and form a pocket for the reception of a card 55 8, upon which may be written the cost price and selling price of the goods contained in the bolt.

From the end of the bolt of cloth 9 I cut a sample strip 10 of a sufficient width to provide a good sample and extending across the whole width of the goods. I take this strip, 60 which is the sample strip, and run it between the down-turned end of the top and the down-turned end of the wire, as shown in Fig. 3, and I run the same up over a tension member 11 which is secured with the body on the under side of the body near the front end thereof to the wire frame, and thence rearwardly beneath the body and over the rear end of the wire frame and thence back toward the front with the front end of the sample hanging down a sufficient distance to give the operator a good hold of the same. Tension member 11 compresses the piece of cloth against the body and provides a tension on the cloth near the front end so that the last 75 sample shall have the same tension on it as the first. I then insert the sample holder containing the sample into the center of the bolt of cloth above the usual center board on which the cloth is folded and push the sample 80 holder into the bolt until it is concealed therein except the front end as shown in Fig. 2. Now should a purchaser desire a sample of the cloth contained in the bolt, all the salesman has to do is to catch hold of the projecting end of the sample strip, pull a sufficient length thereof out and cut it off and give it to the prospective purchaser. This process can be repeated until all of the sample 85 strip is used up or until the bolt of cloth is 90 sold. Should the sample strip be used up before the bolt is sold, the sample holder can be furnished with another sample strip and replaced in the bolt, and after one bolt is sold the sample holder can be used for another 95 bolt of goods. By this device the expense of furnishing samples to prospective purchasers is reduced to a minimum.

Having described my invention, what I claim is:—

1. A sample holder, comprising a wire frame; a metallic body clamped upon the wire frame and having one end thereof terminating just before meeting one end of the wire frame, the other end thereof overlapping 105 the wire frame.

2. A sample holder, comprising a wire frame; a metallic body clamped upon the wire frame and having the front end thereof projecting over the wire frame and bent 110 downwardly and having the edges of the downwardly bent portion bent to form

100

105

110

means to receive a card, said body portion terminating at the rear a little short of the end of the wire frame.

3. A sample holder adapted to be inserted in a bolt of goods, comprising a rectangular wire frame bent downwardly at one end; and a metallic body clamped upon said frame, said body terminating shortly before the unbent end of the frame and being bent over the bent portion of the frame.

4. A sample holder adapted to be inserted in a bolt of goods, comprising a rectangular wire frame bent downwardly on one end; a

sheet metal body resiliently secured over the down turned end and adapted to hold the sample strip against the down turned end; and a tension device situated on the body near the down turned end.

In witness that I claim the foregoing I have hereunto subscribed my name this 14th day of November, 1906.

JOSEPH F. SADLER.
